UNITED STATES PATENT OFFICE.

ALBERT E. HUDSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

METHOD AND MACHINE FOR USE IN CUTTING SHEET MATERIAL.

1,403,497.

Specification of Letters Patent. Patented Jan. 17, 1922.

Application filed July 24, 1919. Serial No. 312,893.

To all whom it may concern:

Be it known that I, ALBERT E. HUDSON, a citizen of the United States, residing at Beverly, in the county of Essex and State 5 of Massachusetts, have invented certain Improvements in Methods and Machines for Use in Cutting Sheet Material, of which the following description, in connection with the accompanying drawings, is a specification, 10 like reference characters on the drawings indicating like parts in the several figures.

This invention relates to dieing out blanks from sheet material and is especially applicable to dieing out blanks from a pile of 15 superposed layers of stock. The invention is herein set forth for the purpose of illustration, but not by way of limitation, with particular reference to its use in connection with presses of the general type illustrated 20 in United States Letters Patent No. 921,503, granted May 11, 1909 on application of Arthur Bates.

Presses of the type described in said Letters Patent, known in the trade as "clicking machines," have been used in large numbers with complete success for dieing out blanks, for example, shoe parts, from leather or fabric. In the use of such presses upon light leather or fabric stock or upon thin 30 piles of fabric stock, ordinarily a single pressure-applying operation is entirely adequate to force the cutting die through the work so as completely to sever a blank. Dieing out blanks from very heavy stock 35 and particularly from substantial piles of layers of stock presents a different problem, due especially to the resistance to cutting action presented by the marked tendency of the piled stock to react from the cutting 40 blow. This is conspicuously true of various fabrics such as are employed in the manufacture of boots and shoes as well as in the manufacture of various kinds of garments.

An object of the present invention is to 45 provide for rapidly and otherwise satisfactorily dieing out blanks from stock of widely varying characteristics. In one aspect the invention aims to increase the output 50 from dieing out operations, of which those above referred to are typical examples, by facilitating dieing out blanks from piles of layers of material so that it will be en-

tirely practicable to cut at one time a relatively large number of layers of stock. In 55 another aspect the invention aims to provide for dieing out blanks from sheets of stock in such manner that all the advantages heretofore resulting from the use of presses of the type above identified may be 60 retained, and at the same time the usefulness of such presses may be still further increased, especially in connection with the dieing out of blanks from piles of sheet material. 65

Presses of the type set forth in said Letters Patent are designed, among other things, to afford opportunity for the utmost discrimination in the examination of the stock to be operated upon, and in the selection of the parts of the stock from which the respective blanks are to be cut. To this end such machines comprise characteristically a rigid cutting bed, a post mounted at one side of the bed, and a relatively long 70 presser member mounted to reciprocate with the post and to swing freely over the bed substantially parallel to it to impart cutting blows to a die freely movable to any desired location upon the bed. In the use of such 75 machines upon heavy work, especially upon piles of superposed layers of material, the resistance to the cutting action afforded by the inherent resilience and tendency of the pile to spring back is considerably augmented by the tendency of the presser member 80 to spring away from the bed resulting from the organization above outlined. 85

In view of the above-entitled and other considerations, the present invention provides for forcing a die step by step through a pile of material by repeated hammer blows delivered against the die so rapidly that the stock can not react from the compression of the initial blow. As herein exemplified, to facilitate the severance of blanks from the pile, an initial hammer blow is delivered against the die of sufficient force 90 substantially to exhaust the compressibility of the pile of stock and force the die part 95 way through the pile, the hammer blow being then repeated so quickly as to force the die through the uncut layers of stock before the stock reacts from the initial blow. 100

In the novel organization of apparatus 105

herein set forth, the results described are secured by the provision of operating mechanism such that, in response to continued movement of a controller in one direction, a presser member delivers rapidly repeated blows against a die. To provide for effective use of the machine whenever it is not advantageous or necessary to treat the work in the manner described, the organization preferably and as shown is such that, at the will of the operator, the presser may be caused either to deliver a single blow against the die and then stop, or to deliver rapidly repeated blows.

15 Other objects and advantages will be apparent from the following detailed description and will be pointed out in the claims.

In the drawings,—

Fig. 1 is a view in side elevation of an improved machine which may be used in the practice of improved methods of cutting sheet material, the starting means being shown in position to cause a single pressure applying operation upon actuation of said means;

Fig. 2 is a detail view, partly in section, of the clutch tripping mechanism,

Fig. 3 is a perspective view of an element of the clutch mechanism, and

30 Figs. 4, 5 and 6 are detail views of the clutch mechanism.

In the illustrative machine the frame 4 carries a work supporting bed 6 and also a presser member 8 which is movable toward 35 and from the bed in pressure applying operations. Rotatably mounted in the frame is a post 10 which carries the presser member, means being provided in the form of a handle 12 for swinging the presser member 40 laterally over the work supporting bed into position over a die located on the work resting on the work supporting bed. In the construction shown the handle 12 is arranged to operate a lever or controller 14 pivoted at 45 16 on the frame of the machine and connected by a link 18 to the clutch mechanism of the main shaft of the machine. Thus, upon depression of the handle 12 the clutch mechanism is operated to connect the power 50 to the shaft and rotation of the latter causes a pressure applying operation of the presser member. Ordinarily the presser member is then moved away from its position over the die and the latter is repositioned on the 55 work, the presser member being at one side where it does not interfere with the proper manipulation of the die and of the work and with the access of light to the work. When the work is prepared for another operation the presser member is swung over 60 the die by means of the handle 12 and the starting or controlling mechanism operated to cause a pressure applying operation of the presser member as above described. For 65 a more detailed description of the construc-

tion of the clicking machine, reference should be had to said Patent No. 921,503.

Mounted in the frame of the machine is the main shaft 20 provided with a driving means in the form of a power pulley 22 and 70 clutch mechanism for operatively connecting the shaft and the pulley, the clutch mechanism being preferably of the type shown in Patent No. 1,011,903 granted December 19, 1911, on an application filed by 75 Arthur Bates, to which patent reference may be had for a more detailed description of those parts of the clutch mechanism which form no part of the present invention. Rigidly attached to the shaft 20 is a clutch 80 member 24 which carries slidably a plunger 26 operable to cause expansion or contraction of the ring 27 through turning of the screw 29, connection being made between the screw and its operating plunger 26 by means 85 of an arm 31 secured to the screw by pin 33 (Fig. 6). Pivoted at 28 on the frame of the machine is a lever 30 having an end portion adapted to operate the plunger 26. When the plunger 26 is released by withdrawing 90 the wedge end of the lever 30, the spring 37 moves said plunger in the direction to turn the screw 29 to expand the ring 27 (partly shown in Fig. 5) so that the latter engages 95 the inside of the flange 39 on the pulley 22 and operatively connects the pulley to the clutch member 24 fixed to the shaft. On the other hand, the wedge end of the lever 30 operates at the proper time to move the plunger 26 against the spring 37 and thereby 100 cause contraction of the ring 27 and release of the pulley from the shaft. In order to lift the member 30 away from the plunger 26 there is provided a tripping mechanism 105 comprising a lever 32 also pivoted at 28 and carrying a plate 34 arranged to engage under a similar plate 36 on a latch member 38 pivoted at 40 on the member 30. Thus, upon upward movement of the lever 32 the latch member 38 is caused to lift the member 110 30 away from the plunger 26 and is then arranged to be released from the lever 32 through a projection 33 on the clutch member 24 engaging the tail 35 of member 38, so that the member 30 dropping back into 115 its operative position may re-engage the plunger 26 at the proper time to cause disconnection of the movable clutch member or flange 39 on the pulley 22 from the stationary clutch member 24 on the shaft. For 120 operating the lever 32 there is provided the hand operated lever 14 connected by the link 18, as above described, to the member 32. In the construction disclosed in the said patent to Bates No. 1,011,903, the member 30 125 operates to retract the plunger 26 at the end of one revolution of the shaft 20. In applicant's invention and as shown in the illustrative construction, the member 30 may be held upwardly away from the plunger 26, 130

so that two revolutions of the shaft may take place, by means now to be described.

Mounted on a vertical shaft 44 in the frame of the machine is a member 46 having a flange portion 48 which is arranged to contact with a projecting portion 50 of the member 30 to hold the latter out of contact with the plunger 26, the said member 46 also having a slot 52 for receiving the projection 50 and thus permitting the end portion of the member 30 to engage the plunger 26. For driving the shaft 44 there is provided a gear wheel 54 on the shaft 20 having teeth constantly in mesh with an intermediate gear 56 on a stub shaft 58 which carries a worm 60 meshing with a worm gear 62 secured to the shaft 44. The relationship of the gears just described is such that two revolutions of the gear 54 are required to effect one revolution of the gear 62 so that the shaft 20 normally revolves twice to one revolution of the member 46. Hence, when the starting lever is depressed, thus lifting the member 30 away from the clutch controlling plunger 26, the projecting portion 50 of the member 30 is moved out of the slot 52 in the member 46 and is engaged with the flange portion 48 of said member during two revolutions of the main shaft, just prior to the termination of which the slot 52 is again brought opposite to the projecting portion 50 of the member 30 so that the latter can drop into position to engage again the clutch operating plunger 26 to unclutch the power pulley from the shaft. While in the construction shown only two pressure applying operations take place upon actuating the starting mechanism through handle 12, the invention is not so limited, it being clear that a plurality of revolutions of the main shaft other than two may be secured in various ways, as for instance, by changing the gears above described.

Means are provided for varying the normal operation of the clutch tripping mechanism just described so that in the present construction but one revolution of the shaft will be produced upon actuating the controlling or starting mechanism. As shown this means comprises devices mounted on the starting lever 14 and arranged to be easily operated by the hand which grasps the handle 12 and having connections for controlling the member 46 for retaining the latter in another operative position for a purpose to be described. Referring to Fig. 1 of the drawings there is disclosed an illustrative embodiment of a controlling means for the clutch tripping mechanism comprising a lever 64 pivoted at 66 to a clamp 68 on the lever 14 and located closely adjacent to the handle 12 so that the lever may be operated by a finger introduced into the ring 70 of the lever. Pivotedly connected to the lever

is a link 72 which is also pivotally connected to a latch 74 pivoted at 76 to a bracket 78 on the starting lever, the latch being normally held in inoperative position by means of a tension spring 80 having its ends connected to the levers 14 and 64 respectively. When the lever 64 is pulled toward the handle 12 the latch 74 is caused to engage over the upper surface of the arcuate portion 82 of a lever 84 pivoted preferably upon the same pivot 16 for the lever 14. Clearly the forward part 82 of the lever 84 must be arcuate in form in order that the latch 74 may engage therewith in whatever position the presser member 8 may occupy. As shown in Figs. 1 and 2, the rear end of the lever 84 is connected by a link 86 to the clutch controlling member 46, the said connection comprising a U-shaped member 88 secured to the link 86 and having pins 90 which extend into a circular groove 92 provided in an upward extension of the member 46, the pin and groove connection permitting rotation of the member 46 and yet serving as a means for connecting the member 46 to the link 86 to be lifted thereby. When the member 46 is lifted from its normal position, a groove or slot 94 in the upper surface thereof is engaged with a lock 96 so that the member 46 will not rotate with its shaft, and thus the slot 52 is maintained opposite to the projecting portion 50 of the member 30 so that the projection may drop into the slot as soon as the member 30 is released by its latch 38 which occurs early in the first revolution of the main shaft 20, as described in said Patent No. 1,011,903. Hence the main shaft will be turned through only one revolution when the member 46 is lifted as described. It should be pointed out that the member 46 is connected to its driving shaft 44 by means of a double armed pin 98 which is received normally into a slot in the lower surface of the member 46. Clearly, when the latter member is raised by the connections described it is moved away from its driving pin 98 and retained against turning through friction with the shaft 44 by means of the lock 96. This latter member or lock is mounted upon a pin 100 extending through the projection 50 and is held normally against a stop 102 by a torsional spring 104 so that the lock 96 may yield laterally if, through incorrect adjustment of the connections in setting up the machine, the member 46 should be positively driven while it is in lifted position. It will be observed that the engaging end of the lock member 96 is roughly wedge shaped so as to turn readily out of the slot 94 should member 46 be driven under abnormal conditions. With the parts arranged in the manner described the main shaft 20 is turned through one complete revolution which effects,

among other things, the turning of the shaft 44 through one-half of a revolution and thus the pin 98 is turned end for end and is then in position to be received within the slot in 5 the bottom face of the member 46 when the latter is lowered at the termination of a single pressure applying operation.

In operating with the machine above described, the work is placed upon the work 10 supporting bed 6 and a die is located in the desired position while the presser member is at one side of the site of operations, and then the presser member is moved laterally toward the die and the starting mechanism 15 actuated while the presser member is moving to cause one or more blows on the die to force the die through the material. If the work consists of a single layer of material, or of two or three layers of light sheet material, 20 the die is readily operated to cut blanks from the material upon a single pressure applying operation of the presser member obtained by operating lever 64 together with the handle 12. If, however, there are many layers of 25 sheet material being operated upon, or a single layer of particularly heavy material, it is sometimes necessary to strike several blows upon the die to force it completely through the work. This can be accomplished 30 by the use of the type of machine like that shown, for instance, in Patent No. 921,503 cited above, simply by depressing the handle of the starting mechanism a plurality of times, once for each pressure applying operation of the presser member. In that case, 35 however, the multiple-layered material which constitutes the work has time to react from the compression of the initial blow that is, to rise between blows, whereas with the construction of the improved machine the blows 40 are repeated so rapidly, upon depressing the handle 12, that the die and the material have no time to react between blows and the die is forced through all the layers of the material with greater certainty and speed. It 45 will be clear, moreover, from this manner of cutting sheet material, that a machine of less power and of less weight may be used in effecting cutting operations on a multiplicity of layers of material than if the machine were organized to cut through all of the layers at one pressure applying operation, the method here practiced involving the cutting of the layers progressively by frequently repeated blows on the die. It should 50 be explained in this connection that while the presser member is so constructed with respect to the work supporting bed as to operate normally to drive a die completely through the material on the bed, the said presser member is so mounted as to yield away from the bed when the die is being driven through work of a denser character than usual, or when many layers of material 55 are being operated upon. This springing of

the presser member away from the bed is dependent upon a certain amount of spring or yielding in the frame of the machine and especially in the approximately C-shaped arm which supports the post for the presser member. It is considered that the method of cutting sheet material herein disclosed is a matter of importance since it provides for increased usefulness of the ordinary clicking press in the cutting of heavy stock 70 and of material in many layers. Furthermore, this machine may be used in the practice of a method of cutting through heavy material or through many layers of material in superposed relation which provides 75 for striking the die at different places by rapidly repeated blows which progressively force the die through the work.

Having described my invention, what I claim and desire to secure by Letters Patent 85 of the United States is:—

1. That improvement in methods of dieing out blanks from sheet material, which consists in piling up layers of material upon a rigid cutting bed, placing the die to be used 90 upon the pile of stock, imparting a hammer blow to the die, and repeating the hammer blow upon the die while the die is in the same location substantially instantaneously and before the stock reacts from the compression 95 of the initial blow to force the die through the pile of material.

2. That improvement in methods of dieing out blanks from sheet material, which consists in piling up layers of material upon a rigid cutting bed, placing the die to be used upon the pile of stock, delivering a hammer blow against the die of sufficient force substantially to exhaust the compressibility of the pile of stock and force the die part way 100 through the pile to facilitate the severance of the blanks from the pile, and repeating the hammer blow to force the die through the uncut layers of stock before the stock reacts 105 from the initial blow.

3. That improvement in methods of dieing out blanks from sheet material, which consists in piling up layers of material upon a rigid cutting bed, placing the die to be used upon the pile of stock and forcing the die 110 step by step through the pile by a plurality of hammer blows delivered against the die so rapidly that the stock cannot react from one blow before the die receives the succeeding blow.

4. That improvement in methods of dieing out blanks from sheet material, which consists in piling up layers of material upon a rigid cutting bed, placing the die to be used upon the pile of stock, and subjecting 115 the die to rapidly repeated blows applied at different points on the die to drive it progressively through the pile of stock.

5. A machine for dieing out blanks from a pile of superposed layers of stock, com- 120

prising a rigid cutting bed, a die, a presser member, and operating mechanism for the presser member including a controller responsive to continued movement in one direction to cause the presser member to deliver repeated blows against the die.

6. A machine for dieing out blanks from superposed layers of stock, comprising a rigid cutting bed, a die, an upstanding post at one side of the bed, an elongated presser member carried by said post for reciprocation therewith, said presser member extending over the bed and being mounted for free swinging movement in a plane parallel to the bed, and operating mechanism organized to counteract the spring of the presser member and its supporting post by effecting rapidly repeated blows of the presser member against the die upon the bed.

7. A machine for dieing out blanks from superposed layers of stock, comprising a rigid cutting bed, a die, an upstanding post at one side of the bed, an elongated presser member carried by said post for reciprocation therewith, said presser member extending over the bed and being mounted for free swinging movement in a plane parallel to the bed, and operating mechanism organized to effect successive blows of the presser member against the die to force the die step by step through the pile of stock with such rapidity as to offset the tendency of the presser to spring away from the bed.

8. A machine for dieing out blanks from superposed plies of stock comprising a rigid cutting bed, a die, a presser member, and operating mechanism organized to effect rapidly repeated blows of said member upon the die to drive the die progressively through the stock.

9. A machine for dieing out blanks from superposed plies of stock comprising a rigid cutting bed, a die, a presser member free at all times to swing in a plane parallel to and near the die, and operating mechanism organized to effect, while the member is in swinging motion, rapidly repeated blows of said member upon the die to drive the die progressively through the stock.

10. A machine for dieing out blanks from superposed plies of stock comprising a rigid cutting bed, a die, a striking or presser member, and operating mechanism including a continuously running driving means, connections between said mechanism and the presser member, a clutch, and a clutch controller all organized to effect reciprocations of the presser member in uninterrupted rapid succession in response to continuous pressure on the controller.

11. A machine for dieing out blanks from superposed plies of stock comprising a rigid cutting bed, a die, a striking or presser member mounted to swing over the die in a plane near the die, and operating mechanism

including a continuously running driving means, connections between said mechanism and the presser member, a clutch, and a clutch controller all organized to effect reciprocations of the presser member in uninterrupted rapid succession in response to continuous pressure on the controller, and while the presser member is free to be swung to positions for delivering the blows at different points on the die.

12. In a machine of the class described, a work supporting bed, a presser member movable toward and from the bed in pressure applying operations, a shaft for operating the presser member, a clutch on the shaft, and means for controlling the clutch to cause a predetermined plurality of operations of the presser member upon a single actuation of said means.

13. In a machine of the class described, a work supporting bed, a presser member movable toward and from the bed in pressure applying operations, a shaft for operating the presser member, a clutch on the shaft, and means for controlling the clutch to cause a single operation or a predetermined plurality of operations of the presser member at the will of the operator following a single actuation of said means.

14. In a machine of the class described, a work supporting bed, a presser member movable toward and from the bed in pressure applying operations, a shaft for operating the presser member, a clutch on the shaft, means for controlling the clutch to cause a predetermined number of operations of the presser member upon a single actuation of said means, and means for varying the control exercised by the first-mentioned means.

15. In a machine of the class described, a presser member, a work supporting member, means for causing pressure applying movements of the presser member, and means for controlling the said first-mentioned means to cause a predetermined plurality of operations of the presser member upon a single actuation of the controlling means.

16. In a machine of the class described, a presser member, a work supporting member, means for causing pressure applying movements of the presser member, and means for controlling said first-mentioned means to cause a single operation or a predetermined plurality of operations of the presser member at the will of the operator in either case upon a single actuation of the controlling means.

17. In a machine of the class described, a presser member, a work supporting member, means for causing pressure applying movements of the presser member, means for controlling the first-mentioned means to cause a predetermined number of operations of the presser member upon a single

actuation of the controlling means, and means for varying the control exercised by the last-mentioned means.

18. In a machine of the class described, a work supporting bed, a presser member, power means for moving the presser member toward and from the bed, starting mechanism for controlling the power means and normally operative to cause a plurality of pressure applying movements of the presser member, and means mounted on the starting mechanism for varying the operation thereof.

19. In a machine of the class described, a work supporting bed, a presser member, power means for moving the presser member toward and from the bed, a starting mechanism for controlling said power means comprising a member for holding the starting mechanism in operation during a plurality of operations of the presser member, and means for rendering said member inoperative at the will of the operator.

20. In a machine of the class described, a work supporting bed, a presser member movable toward and from the bed in pressure applying operations, power means for operating the presser member including a shaft, a clutch mechanism on said shaft, a starting mechanism for tripping said clutch comprising a member constructed and arranged to hold the starting mechanism in clutch tripping position, and means mounted on the starting mechanism for controlling said member so as to vary the normal operation of the starting mechanism.

21. In a machine of the class described, presser members movable toward and from each other in pressure applying operations, power means for causing relative movement of the presser members comprising a shaft, a clutch mechanism on the shaft, means for tripping the clutch to connect the same to the shaft and cause a plurality of revolutions of the latter upon one actuation of said tripping means, and means under the control of the operator for varying the operation of said tripping means, thereby to secure one or a plurality of pressure applying operations at the will of the operator.

22. In a machine of the class described, presser members movable toward and from each other in pressure applying operations, power means for causing relative movement of the presser members comprising a shaft, a clutch mechanism on the shaft, means for tripping the clutch mechanism constructed and arranged to cause a plurality of revolutions of the shaft, said tripping means comprising a member which is operative to hold the tripping means operative during said plurality of revolutions of the shaft, and means under the control of the operator for varying the position of said member and thereby changing the normal

operation of said tripping means to secure one or a plurality of pressure applying operations at the will of the operator.

23. In a machine of the class described, presser members movable toward and from each other in pressure applying operations, power means for causing relative movement of the presser members comprising a shaft, a power pulley on the shaft, clutch mechanism for connecting the pulley to the shaft, a starting mechanism for tripping the clutch mechanism and thus connecting said pulley to said shaft comprising a rotary member operatively connected to the shaft to be driven thereby, and means under the control of the operator to move said member and thereby vary the operation of said starting mechanism to secure one or a plurality of pressure applying operations at the will of the operator.

24. In a machine of the class described, presser members movable toward and from each other in pressure applying operations, power means for causing relative movement of the presser members comprising a shaft, a power pulley on the shaft, clutch mechanism for connecting said pulley to said shaft, starting mechanism for tripping the clutch comprising a rotary member arranged to be driven by said shaft, and means under the control of the operator to disconnect said member from the shaft and thus vary the operation of the starting mechanism in such manner that the number of revolutions of the shaft is effected to secure one or a plurality of pressure applying operations at the will of the operator.

25. In a machine of the class described, a work supporting bed, a presser member movable toward and from the bed in pressure applying operations, power means comprising a shaft for operating the presser member, a clutch on the shaft, a starting lever having a handle movable with the presser member, connections between the lever and the clutch for controlling the latter, a lever mounted on the first mentioned lever, and connections between the second lever and the clutch mechanism so arranged that simultaneous operation of both levers results in the clutching of the shaft for a single pressure applying operation.

26. In a machine of the class described, a work supporting bed, a presser member movable toward and from the bed in pressure applying operations, power means comprising a shaft for operating the presser member, a clutch on the shaft, a lever for directly controlling the clutch, a rotatable member for controlling the lever, and two manually controllable levers mounted to move with the presser member for controlling the first mentioned lever and the rotatable member respectively, the arrangement being such that one or a plurality of pres-

sure applying operations may be initiated by the operator through control of the levers movable with the pressure member.

27. In a machine of the class described, 5 a work supporting bed, a presser member movable toward and from the bed in pressure applying operations, power means comprising a shaft for operating the presser member, a clutch on the shaft, a lever for 10 directly controlling the clutch, a rotatable member arranged to be operated by said shaft to control said lever, and two levers mounted to move with the presser member and having connections with the first men- 15 tioned lever and with said rotatable member respectively and operable to effect one or a plurality of revolutions of the shaft at the will of the operator to cause one or a plurality of pressure applying operations of 20 the presser member.

28. In a machine of the class described, presser members relatively movable toward and from each other in pressure applying operations, power means comprising a shaft 25 for causing such relative movement of the presser members, a power pulley, a clutch for operatively connecting the shaft to the said pulley, a manually operable lever on one of the presser members having connec- 30 tions for causing the connection of the shaft and pulley for a predetermined number of revolutions, and a second lever mounted on the first mentioned lever and having connections arranged to change the operation 35 of the clutch as effected by operation solely of the first-mentioned lever.

29. In a machine of the class described, presser members relatively movable toward and from each other in pressure applying 40 operations, power means comprising a shaft for causing such relative movement of the presser members, a driven member freely rotatable with respect to the shaft, a clutch for operatively connecting the shaft to the 45 driven member, a manually controllable lever having connections for operating the clutch, and a member controlled by the shaft for locking the said connections in the position to which they have been moved by 50 the manipulation of the starting lever so as to ensure a predetermined number of revolutions of the shaft.

30. In a machine of the class described, presser members relatively movable toward 55 and from each other in pressure applying operations, power means comprising a shaft for causing such relative movement of the presser members, a power pulley, a clutch for operatively connecting the shaft to the 60 said pulley, a lever movable with one of the presser members and manually operable for causing the connection of the shaft and pulley for a plurality of revolutions of the pulley, and a second lever movable with the 65 first mentioned lever and having connec-

tions arranged to change the operation of the clutch so that but one revolution of the shaft follows manipulation of both levers.

31. In a machine of the class described, 70 presser members relatively movable toward and from each other in pressure applying operations, power means comprising a shaft for causing such relative movement of the presser members, a driven member freely rotatable with respect to the shaft, a clutch 75 for operatively connecting the shaft to the driven member, a manually controllable lever having connections for operating the clutch, a member controlled by the shaft for locking the said connections in the position 80 to which they have been moved by the manipulation of the starting lever so as to ensure a predetermined number of revolutions of the shaft, and a second lever manually operable to render said locking means 85 inoperative thereby causing a single revolution only of the shaft upon manipulation of the first mentioned lever.

32. In a machine of the class described, 90 presser members relatively movable toward and from each other in pressure applying operations, power means comprising a shaft for causing such relative movement of the presser members, a driven member rotatable independently of the shaft, a clutch for 95 operatively connecting the driven member to the shaft, a lever movable with one of the presser members and operable for controlling the clutch, connections between said member and the clutch comprising a member 100 directly controlling the clutch, and a member driven by the shaft for locking the clutch controlling member in inoperative position during a predetermined number of revolutions of the shaft. 105

33. In a machine of the class described, 110 presser members relatively movable toward and from each other in pressure applying operations, power means comprising a shaft for causing such relative movement of the presser members, a driven member normally rotatable independent of the shaft, a clutch for operatively connecting the driven member and shaft, a lever having connections for controlling the clutch, a lock 115 controlled by the shaft for locking the said connections in inoperative relation to the clutch during a predetermined number of revolutions of the shaft, and a second lever movable with one of the presser members 120 and also manually controllable for moving the lock so as to render it inoperable thereby changing the operation of the said connections whereby a different number of revolutions of the shaft takes place upon manipulation of the first mentioned lever. 125

34. In a machine of the class described, 130 presser members relatively movable toward and from each other in pressure applying operations, power means comprising a shaft

for causing such relative movement of the presser members, a driven member rotatable independently of the shaft, a clutch for operatively connecting the driven members to the shaft, a manually operable lever for initiating operation of the machine having connections with the clutch comprising a member directly controlling the clutch, and a member driven by the shaft for locking the clutch controlling member in inoperative position during a predetermined number of revolutions of the shaft.

35. In a machine of the class described, presser members relatively movable toward and from each other in pressure applying operations, power means comprising a shaft for causing such relative movement of the presser members, a driven member normally rotatable independent of the shaft, a clutch for operatively connecting the driven member and shaft, a lever having connections for controlling the clutch, a lock controlled by the shaft for locking the said connections in inoperative relation to the clutch during a predetermined number of revolutions of the shaft, and a second lever also manually controllable for moving the lock so as to render it inoperable thereby changing the operation of the said connections whereby a different number of revolutions of the shaft takes place upon manipulation of the first mentioned lever.

36. In a machine of the class described, presser members relatively movable toward and from each other in pressure applying operations, power means comprising a shaft

for causing such relative movement of the presser members, a driven member normally rotatable independently of the shaft, a clutch for operatively connecting the driven member and shaft, a lever movable with one of the presser members and having connections for operating the clutch, and a second lever mounted on the first mentioned lever and having connections controlled by the shaft for varying the operation of the first mentioned connections whereby one or a plurality of rotations of the shaft may be caused at the will of the operator upon manipulation of the first mentioned lever.

37. In a machine of the class described, presser members relatively movable toward and from each other in pressure applying operations, power means comprising a shaft for causing such relative movement of the presser members, a driven member normally rotatable independently of the shaft, a clutch for operatively connecting the driven member and shaft, a lever having connections for operating the clutch, and a second lever mounted to move with one of the presser members and having connections controlled by the shaft for varying the operation of the first mentioned connections whereby one or a plurality of rotations of the shaft may be caused at the will of the operator upon manipulation of the first mentioned lever.

In testimony whereof I have signed my name to this specification.

ALBERT E. HUDSON.
